UNITED STATES PATENT OFFICE.

EDWARD C. SASNETT, OF WASHINGTON, DISTRICT OF COLUMBIA.

RAILWAY SIGNALING.

Application filed December 7, 1922. Serial No. 605,482.

To all whom it may concern:

Be it known that EDWARD C. SASNETT, a citizen of the United States, residing at Washington, in the District of Columbia, 5 has invented certain new and useful Improvement in Railway Signaling, of which the following is a specification, reference being had therein to the accompanying drawing.

10 My invention relates to railway signaling and particularly to automatic train controlling systems of the continuous indication type.

The object of my invention is to provide 15 a continuous indication third rail system having provisions to prevent the reception of a false indication by a following train when it enters an occupied block. To this end, the system of the present invention includes means responsive to the entry of a 20 train into an occupied block to control the signaling energy supplied to the third rail section pertaining to that block. This means may comprise an electro-responsive device 25 controlled jointly by at least two adjacent track relays, in such a manner that said device will be energized, or if already energized, will remain energized, when a train actuates said relays in a certain sequence, but 30 which will be deenergized if a second train should actuate the first relay while the second relay is still under the control of the first train. An electro-responsive device controlled in this manner is adapted to other 35 uses than the specific use disclosed herein, and I therefore intend to make broad claims for this element of the system.

Referring to the accompanying drawing, which illustrates diagrammatically a form 40 of my invention:—

The track is divided by insulated joints into sections A, A', B, B' etc. The sections A, A' constitute a block and the sections B, B', a succeeding block. The sections A, 45 B are preliminary sections and are relatively short as compared with sections A', B'. Each section forms part of a closed track circuit, which includes a track battery at one end and a track relay at the other end. 50 As is well understood, when a train enters a section the wheels and axles thereof short circuit the track battery and cause the track relay to be deenergized and thereby to open its front contacts and close its back 55 contacts.

For the purpose of illustrating the appli-

cation of my invention to continuous indication train controlling systems, I have shown a signal conductor S, or third rail, supported adjacent and parallel to the track 60 in any approved manner and divided into insulated sections corresponding to the block sections. The train equipment includes an electroresponsive device 23 connected on one side to the wheels and axles and on the other side to a shoe or trolley adapted to contact the conductor S. The electro-responsive device may be a relay having a neutral armature adapted to apply the brakes when opened, and a polarized armature adapted to display a caution signal or set in operation a speed limit device or both, in a manner which will be obvious to those skilled in the art. 65

The track relays C, D, C', D' control stick 70 relays E, F, E', F', and the relays F, F' are adapted to connect batteries G, G', respectively, across the respective sections of signal conductor S and the track, with one polarity or the other depending upon the 75 direction of current through said relays.

The system operates in the following manner:

When the train shown at the left enters section A and the two blocks ahead are 80 clear, track relay C is deenergized, thereby closing a circuit through stick relay E from battery G' by way of front contacts 1 and 2, line conductor 3, back contact 4, front contact 5, conductor 6, relay E, common 85 return R, front contact 8, front contact 9, conductor 10 to battery G'. Relay E thereupon picks up closing a stick circuit through itself exclusive of front contact 5, this circuit including back contact 4, front contact 11 and conductor 12 and being otherwise the same as the pick up circuit just traced. The stick circuit of relay E holds 90 said relay energized when the pick up circuit is broken at front contact 5 by the entry of the train into section A'. Relay E will accordingly remain energized until the train passes entirely off section A, 95 breaking the stick circuit at back contact 4. The energization of relay E closes the following circuit through relay F: battery G', front contacts 1 and 2, conductor 3, front contact 13, relay F, common return, conductor 7, front contacts 8 and 9, conductor 10, battery G'. Relay F then closes a stick 100 circuit through itself exclusive of front contact 13, said circuit including front contact 110

105

110

tact 14, back contact 15, conductor 16, front contact 17, conductor 18, relay F, to common return. Hence relay F will remain energized when the train wholly leaves section A causing the pick up circuit to be opened at front contact 13. When relay F picks up, battery G is connected across the signal conductor S and the track and the following circuit is completed: battery 10 G, conductor 19, contact 20 of polarized armature, front contact 21 of the neutral armature, conductor 22, the track rails, the wheels and axle, relay 23, the sliding contacts 24, conductor S, conductor 25, front 15 contact 26, polarized contact 27, conductor 28 back to battery. The train entering block A, A' will therefore receive a clear indication. If a train had been in section B', however, when the train under consideration entered section A, relay D' would have been deenergized, and hence the direction of current through relay F would have been reversed, and the polarized armature of said relay would have made contact 25 with 29 and 30 instead of 27 and 20. This would have reversed the direction of current through relay 23, opening the polarized contact thereof and displaying a caution signal and setting in operation a suitable speed limit device or a device governed by the travel of the train which would cause the brakes to be set after a predetermined movement of said train in section A'.

It will be observed that as long as the block A, A' is occupied by a vehicle it is impossible for a second vehicle to enter this block under a clear indication. If a second vehicle should attempt to enter from the left, it would cause relay C to be deenergized, thereby breaking the retaining circuit of relay F at front contact 14. If a second vehicle should attempt to back into the block from the right, the retaining circuit of relay F would be broken at front 45 contacts 1 and 9. Hence it is clear that under no conditions is it possible for two vehicles in the same block to receive clear indications.

It is to be understood that the drawings are merely designed to show an illustrative example of the invention. Various modifications in the circuit arrangements for controlling the electro-responsive device F are possible without changing the essential character of the invention. The invention is not concerned with the means for transmitting energy from the track to the controlling devices on the train. The conductive system shown is merely for the purpose of illustration, and it will be obvious that the invention is equally applicable to inductive systems or to systems of the radio type.

I claim:

1. In a block system, two adjacent track circuit sections, each including a relay, an

electro-responsive device, means controlled by the track relays of said sections for energizing said device when a train enters the first track section and for retaining said device energized when the train passes on 70 to the second track section and wholly off said first track section, and means for de-energizing said device when a second train enters said first track section while the first train is on said second track section. 75

2. In a block system, two adjoining track-circuit sections, each including a relay, an electro-responsive device, an energizing circuit for said device controlled by the track relays of said sections and a retaining circuit for said device including a front contact of one of said relays, a back contact of the other relay and a contact which is closed only when said device is energized. 80

3. In a block system, two adjoining track-circuit sections each including a relay, a relay having a pick-up circuit controlled by the track relays of said sections and a stick circuit closed only when said track relays are actuated in a certain sequence, 85 said stick circuit including a front contact of one of said track relays.

4. In a block system, two adjoining track-circuit sections, each including a relay, an electro-responsive device, means controlled by the track relays of both sections for holding said device energized when a train enters the first track section and until it has passed entirely on to the second track section, a second electro-responsive device 100 having a pick-up circuit controlled by the first mentioned device and a holding circuit controlled by both of said track relays. 95

5. In a block system, two adjacent track-circuit sections, each including a relay, a relay having a pick-up circuit including a back contact of the first track relay and a front contact of the second track relay, a holding circuit for said relay including a back contact of said first track relay and a front contact of said relay, a second relay, a pick-up circuit for said second relay including a front contact of said first relay and a holding circuit for said second relay including a front contact of said first track relay, a back contact of said second track relay and a front contact of said second relay. 110 115

6. In a block system, a track divided into insulated blocks, each block comprising a short preliminary track section and a main track section and each section forming part of a closed track circuit including a track relay, an electro-responsive device for each block having an energizing circuit controlled jointly by the preliminary track relay and the main track relay of the respective block, and a retaining circuit for said electro-responsive device including in series 125 a front contact of the preliminary track re- 130

lay and a back contact of the main track relay.

7. In a block system, a track divided into insulated blocks, each block comprising a short preliminary track section and a main track section and each section forming part of a closed track circuit having a relay, an auxiliary relay for each block having a pick-up circuit including a back contact of the preliminary track-section relay and a front contact of the main track-section relay of the respective block, a holding circuit for said auxiliary relay including a back contact of said preliminary track-section relay and a front contact of said auxiliary relay, an electro-responsive device, a pick-up circuit for said device including a front contact of said auxiliary relay, and a holding circuit for said device including a front contact of said preliminary track-section relay and a back contact of said main track-section relay.

8. A continuous indication block signaling system comprising a track divided into insulated sections each of which forms part of a closed track circuit including a relay, each block being constituted by at least two track sections, an electro-responsive device for each block, means controlled by the track relays of a block for energizing the electro-responsive device of that block and maintaining said device energized when a train enters said block travelling in a given direction and until it passes into the block ahead, means for deenergizing said device when a second train enters said block prior to the passage of the first train thereout, and a signaling circuit closed by the energization of said device.

9. In a continuous indication block signaling system, two adjacent track circuit sections each including a relay, an electro-responsive device, means controlled by the track relays of said sections for energizing said device when a train enters the first track section and for retaining said device energized when said train passes on to the second track section and entirely off said first track section said means being rendered inoperative to retain said device energized when a second train enters said first track section while the first train is on said second track section, means for supplying signaling energy to a train while passing over said track sections when said device is energized, and a translating device on said train responsive to said energy.

10. In a continuous indication block signaling system, two adjoining track circuit sections each including a relay, an electroresponsive device, an energizing circuit for said device controlled by the track relays of said sections and a retaining circuit for said device including a front contact of one of said relays, a back contact of the

other relay and a contact which is closed only when said device is energized, means rendered operative by the energization of said device for supplying energy to a train while passing over said track sections, and a translating device on said train controlled by said energy. 70

11. In a continuous indication block signaling system, two adjoining track circuit sections, each including a relay, a relay having a pick-up circuit controlled by the track relays of said sections and a stick circuit closed only when said track relays are actuated in a certain sequence, said stick circuit including a front contact of one of said track relays, means rendered operative by the energization of said device for supplying energy to a train while passing over said track sections, and a translating device on said train responsive to said energy. 80

12. In a continuous indication block signaling system, two adjoining track circuit sections each including a relay, an electro-responsive device, means controlled by the track relays of both sections for holding said device energized when a train enters the first track section and until it has passed entirely on to the second track section, a second electroresponsive device having a pick-up circuit controlled by the first mentioned device and a holding circuit controlled by both of said track relays, means rendered operative by the energization of said second electro-responsive device for supplying energy to a train while passing over both of said track sections, and a translating device on said train responsive to said energy. 90

13. In a continuous indication block signaling system, a track divided into insulated blocks, each block comprising a short preliminary track section and a main track section and each section forming a part of a closed track circuit including a relay, an electroresponsive device for each block having an energizing circuit controlled jointly by the preliminary track section relay and the main track section relay of the respective block, a retaining circuit for said electro-responsive device including in series a front contact of the preliminary track section relay and a back contact of the main track section relay, means rendered operative by the energization of said electroresponsive device for supplying energy to a train while passing over the track sections of the block pertaining to said device, and a translating device on said train responsive to said energy. 110

14. A continuous indication block signaling system, comprising a track divided into insulated block sections, each block section consisting of a preliminary short section and a main section each of which forms part of a closed track circuit including a relay, 120

an electro-responsive device for each block under the control of the track relays of the respective block and of the block in advance, means for energizing said device 5 when a train enters the preliminary track section of the block pertaining thereto and for retaining said device energized during the passage of the train in said block, means rendered operative by the energization of 10 said device for supplying signaling energy to a train during its passage over the block pertaining to said device, a translating device on said train responsive to said energy, and means for deenergizing said electro-responsive device if a second train enters said block from either end.

15. A continuous indication block signal system comprising a track divided into block sections, an electro-responsive device 20 associated with each block section, train controlling circuits controlled by said electro-responsive devices, means for energizing said electro-responsive device when a train enters the block pertaining thereto, and 25 means for deenergizing said device when a second train enters said block before the latter has been cleared by the first train.

16. In a continuous indication train controlling system, a track divided into block 30 sections, sources of current and track relays connected to said sections, a conductor parallel to the track divided into corresponding sections, means controlled by the track relays for supplying signaling energy 35 to the conductor sections in accordance with traffic conditions, said means being responsive to the entry of a second vehicle into an occupied block.

17. A continuous indication train controlling system comprising a track divided into block sections, sources of current and track relays connected to said sections, a conductor parallel to the track divided into corresponding sections, a vehicle having a contact engaging said conductor and having an electro-responsive device connected to said contact adapted to control suitable governing means, means controlled by said track 45 relays for supplying signaling energy to 50 said conductor sections when a vehicle is travelling under clear traffic conditions in the blocks pertaining thereto, said means being under the control of a second vehicle entering an occupied block.

55. 18. A continuous indication train controlling system comprising a track divided into block sections, sources of current and track relays connected to said sections, a conductor parallel to the track divided into corresponding sections, a vehicle having a contact engaging said conductor and an electro-responsive device connected to said contact adapted to control suitable vehicle governing means, connections controlled by said track relays 60 65 for supplying signaling energy to said con-

ductor sections in accordance with traffic conditions, and an electro-responsive device associated with each block section under the control of track relays and controlling said connections, said electro-responsive device 70 being controlled by a second vehicle entering an occupied block to prevent said second vehicle from receiving a clear indication.

19. A continuous indication train controlling system comprising a track divided into 75 block sections, sources of current and track relays connected to said sections, a conductor parallel to the track divided into sections, a vehicle having a contact engaging said conductor and an electro-responsive device connected to said contact adapted to control suitable indication means, means for supplying signaling energy to said conductor sections in accordance with traffic conditions, and means to affect the supply of signaling energy when a second vehicle enters 80 an occupied block.

20. A continuous indication train controlling system comprising a track divided into block sections, sources of current and track 90 relays connected to said sections, a conductor parallel to the track, a vehicle having a contact engaging said conductor and an electro-responsive device connected to said contact adapted to control suitable indication 95 means, means controlled by said track relays for supplying signaling energy to said conductor, said means being responsive to the entry of a second vehicle into an occupied block to prevent said second vehicle 100 from receiving a clear indication.

21. In a continuous indication train controlling system, a track divided into block sections, sources of current and track relays connected to said sections, a conductor parallel to the track divided into corresponding sections, means controlled by the track relays for supplying signaling energy to the conductor sections, and means to affect the 105 energy being supplied to a conductor section when the block pertaining thereto is occupied and a second vehicle enters said block.

22. In a continuous indication train controlling system, a track divided into block 115 sections, sources of current and track relays connected to said sections, a conductor parallel to the track divided into corresponding sections, means controlled by the track relays for supplying signaling energy to the 120 conductor sections, vehicles travelling on said track having contacts engaging said conductor and having electro-responsive devices connected to said contacts, said means being responsive to a following vehicle to 125 control the signaling energy being supplied to the vehicle in advance thereof.

23. In a continuous indication train controlling system, a track divided into block sections, sources of current and track relays 130

- connected to said sections, a conductor parallel to the track, means controlled by the track relays for supplying signaling energy to said conductor, vehicles travelling on said track having contacts engaging said conductor and having electro-responsive devices connected to said contacts, said means being actuated when a following vehicle approaches within a predetermined zone of the vehicle in advance to control the signaling energy being supplied to the vehicle in advance.
24. In a continuous indication train controlling system, a track, sources of current and track relays connected to said track, a conductor parallel to the track, means controlled by the track relays for supplying signaling energy to said conductor, vehicles travelling on said track having contacts engaging said conductor and having electro-responsive devices connected to said contacts, said means being responsive to a following vehicle and being actuated when said following vehicle approaches within a predetermined zone of the vehicle in advance to control the signaling energy being supplied to said vehicle in advance.
25. In a continuous indication train controlling system, a track, sources of current and track relays connected to said track, a conductor parallel to the track, means controlled by the track relays for supplying signaling energy to said conductor, vehicles traveling on said track having electro-responsive devices adapted to be energized from said conductor, said means being responsive to a following vehicle and being actuated when a following vehicle approaches within a predetermined zone of the vehicle in advance to control the signaling energy being supplied to the vehicle in advance.

In testimony whereof I hereunto affix my signature.

EDWARD C. SASNETT.
